UNITED STATES PATENT OFFICE.

HEINRICH KOPPERS, OF ESSEN-ON-THE-RUHR, GERMANY, ASSIGNOR TO H. KOPPERS COMPANY, OF CHICAGO, ILLINOIS, A CORPORATION.

PROCESS OF SEPARATING THE HYDROCARBONS CONTAINED IN NATURAL GAS.

1,107,803.

Specification of Letters Patent. Patented Aug. 18, 1914.

Application filed July 8, 1913. Serial No. 777,830.

To all whom it may concern:

Be it known that I, HEINRICH KOPPERS, engineer, residing at Moltkestrasse 29, Essen-on-the-Ruhr, in Prussia, Germany, have 5 invented a certain new and useful Process of Separating the Hydrocarbons Contained in Natural Gas, of which the following is a specification.

This invention relates to a novel process 10 of separating hydrocarbons contained in the natural gas, which process is preferably carried out in an apparatus such as shown in the accompanying drawing, in which—

Figure 1 is a longitudinal section, and 15 Fig. 2 a cross section of the apparatus.

The apparatus is in the form of a bell washer of known type, comprising a plurality of superimposed divisions 10, provided with bases 11. Each chamber has an inlet 20 conduit 12 and a discharge conduit 13, the chambers 10 being so arranged relatively to each other that the inlet conduit of one chamber forms an extension of the discharge conduit of the other chamber. In the bases 25 11 there are slots 14 having a raised edge 15, over which are placed caps 16, said caps having jagged openings 17. The uppermost division 10 has an inlet pipe 18 for the washing oil and a discharge pipe 19 for the gas. 30 The lowermost division is provided with a discharge pipe 20 for the washing oil. The whole apparatus is inclosed in a wrought-iron casing 21 through which the pipes 18, 19, 20 pass, while the pipe 22 for introducing 35 the gas to be washed is connected to the outer casing 21, a hole 23 giving access to the inner washing apparatus.

The washing oil introduced at a suitable pressure through the pipe 18 successively 40 fills the several divisions 10 by flowing over the caps 16 to the outlet 13, whence it passes by way of the inlet 12 into the next chamber. The gas under pressure to be washed enters 45 by way of the pipe 22 into the intermediate space between the outer casing 21 and the inner washing apparatus, whence it passes through the opening 23 into the lowermost division. The gas then passes through the slots 14 and the tooth shaped openings 17 50 into the washing liquid, whereby a free exchanging action is caused to take place. The washed gas leaves the apparatus by the pipe 19.

The object of the special construction of the apparatus described is as follows: Wrought 55 iron is a metal capable of withstanding high pressures, on the other hand, however, it is more liable to be chemically attacked than cast iron, and the possibilities of shaping wrought iron are limited. As a cast-iron 60 washing apparatus of this description cannot very well be built for high pressures the wrought iron casing is provided to take the pressure so that compensation between the outer and inner super-pressure is provided. 65 In this manner the gas can be washed under pressure while retaining the approved forms of bell washers. The detail construction is immaterial, the point being to enable the washing device of any desired 70 shape to be made of cast-iron which has more resistance from a chemical point of view, while avoiding danger of destruction by the pressure present.

What I claim as my invention and desire 75 to secure by Letters Patent of the United States is:—

1. Process of separating hydrocarbons contained in the natural gas which consists in driving said gas under pressure into a 80 wrought iron jacket, and conveying the gas from said jacket into a cast iron bell washer inclosed by the jacket and containing a hydrocarbon-dissolving oil, whereby the bell washer is subjected to like exterior and in- 85 terior pressure.

2. Apparatus of the character described comprising a cast iron bell washer, a wrought iron casing surrounding said washer to form an intervening jacket, means 90 for admitting a gas under pressure into said jacket, and means for admitting said gas from the jacket into the bell washer, whereby the gas pressure is taken up by the wrought iron casing while the cast iron bell 95 washer is relieved by being subjected to like exterior and interior pressure.

In testimony whereof I have signed my name to this specification in the presence of two subscribing witnesses.

HEINRICH KOPPERS.
